QUIMBY N. EVANS, OF NEW YORK, N. Y., ASSIGNOR TO EVANS, ALMIRALL & CO., OF NEW YORK, N. Y., A FIRM.

STEAM-HEATING SYSTEM.

1,087,284.

Specification of Letters Patent.

Patented Feb. 17, 1914.

Application filed January 18, 1911, Serial No. 603,311. Renewed August 2, 1913. Serial No. 782,710.

To all whom it may concern:

Be it known that I, QUIMBY N. EVANS, a citizen of the United States, residing in the borough of Brooklyn, county of Kings, 5 city and State of New York, have invented certain new and useful Improvements in Steam-Heating Systems, of which the following is a specification.

This invention relates to steam heating 10 apparatus adapted for the heating of buildings, wherein the radiators are commonly provided with the usual thermostatic air valves which contract when cold to admit air, and when heated expand to close the air 15 vent. When such air valves are uninclosed, it occasionally happens that through improper adjustment or through wear, they will leak or drip, sometimes damaging carpets or decorations. To obviate this the discharge 20 from these air valves is in some cases carried through a small pipe to a collecting vessel in the lower part of the building from which any accumulating water has been run off. In such installations it is desirable to 25 provide a suction device whereby a partial vacuum may be maintained in the air-pipe; this has the advantage of hastening the heating up of the radiators when steam is turned on.

30 The present invention provides an improved and simplified apparatus for continuously maintaining a suction in the air or vent pipe leading from the radiators of a steam heating system.

35 The figure of the accompanying drawing is an elevation partly in vertical section showing my invention as applied in connection with two steam radiators supposed to be controlled with others at a higher level 40 in any building.

The radiators A, A are or may be of any suitable or known construction having steam inlet valves *a a* opening from any source of steam at any suitable pressure.

45 *b b* are the inclosed air valves which are the usual thermostatic valves, and from their inclosing casing their lead downwardly vent or drip pipes *c c*. These pipes from the several radiators ordinarily lead to the pipe 50 *d* which enters the basement or cellar and which in this instance leads to a suction column B consisting of any suitable pipe, say for example, three to four inches in diameter, having a trap or seal C at its lower

part and discharging through a waste pipe 55 D to the sewer or any convenient outlet. The column B is provided with means for creating a partial vacuum so as to maintain a slight suction in the pipes *c d*. A water gage *e* is applied by which the extent of 60 this vacuum may be readily ascertained. A water pipe E, leading from any suitable source of water such as a city water main, leads to a valve F, and thence through a pipe E' to the water column B which is connected at *f* preferably obliquely as shown, so as to discharge a stream of water into the column B, whereby to condense any steam or vapor therein, and by reason of such condensation and also by reason 70 of its injector action, to create the desired suction or partial vacuum in the column. The admission of water for this purpose is regulated automatically and in proportion to the degree of vacuum 75 that exists, as determined by a diaphragm regulator G. This regulator comprises a diaphragm *g* of any suitable flexible material, mechanically connected to a lever H pivoted on a fixed fulcrum *h* and connecting 80 with the stem of the valve F. The lever carries also an adjustable weight *i* by which the degree of vacuum to be maintained may be adjusted. The diaphragm *g* closes the top 85 of a chamber I which communicates indirectly with the column B. This communication is made through a pipe *j*, a vertical pipe J constituting another column, and from the upper part of this pipe through a pipe *k* leading to the upper part of the column B. A branch water pipe L controlled by a hand valve *l* discharges into the upper 90 part of the column J.

In operation the valve *l* will be open very slightly so as to permit a slow flow or leakage into the top of the column J, whereby this column is normally kept full or substantially so, of water. The weight of this water causes an upward pressure in the chamber I tending to lift the diaphragm *g* 95 against the weight of the connected parts, which may be varied by the adjustment of the weight *i*. Any other adjustable opposing means might be substituted. When the pressure of water exceeds the opposing 100 forces the diaphragm *g* is lifted, thereby moving the lever H and opening the valve F. This permits a flow of water through 105

the pipe E' into the column B, which not only condenses any steam therein, but carries with it enough of the air to cause a partial vacuum or suction in the column, the 5 excess water flowing off through the trap C. As soon as the vacuum thus created becomes sufficient, the suction communicated through the pipe k lifts the water in the column J, being aided by the pressure of the parts 10 resting on the diaphragm g, and the latter is proportionately lowered thereby through the lever H, closing or partially closing the valve F and cutting down the supply of water. In practice, the diaphragm will assume such position that the valve F is 15 kept open just enough to permit a sufficient stream of water to enter the column B to maintain the precise degree of vacuum or rarefaction for which the apparatus is set 20 by reason of the adjustment of the weight i. Any diminution of the vacuum permits the water in column J to exert greater pressure upon the diaphragm and lift it, thereby partially opening the valve and increasing the 25 flow of water and thereby intensifying the vacuum; and the contrary operation occurs when the prescribed vacuum is exceeded.

The apparatus described constitutes a very simple, effective and reliable means for 30 maintaining the desired slight partial vacuum in the air pipes or vent pipes c d, whereby whenever the air valves of the radiators are open the air is drawn from the radiators, thereby facilitating the admission of steam 35 thereto when the steam valves are opened.

The apparatus is of especial value in connection with a low pressure heating system.

What I claim is:—

1. A suction device for a steam heating system comprising a trapped condensing 40 column, a valved water inlet thereto, and means controlled by the vacuum in said column for operating the valve whereby automatically to maintain a prescribed vacuum. 45

2. A suction device for a steam heating system comprising a trapped condensing column, a valved water inlet thereto, a diaphragm for operating the water inlet valve, and a duct communicating between said 50 diaphragm and column.

3. A suction device for a steam heating system comprising a trapped condensing column, a valved water inlet thereto, pressure-operated means for controlling the inflow of water, and a water column communicating at its bottom with said pressure-operated means and at its top with said 55 trapped column.

4. A suction device for a steam heating 60 system, comprising a trapped condensing column, a valved water inlet thereto, pressure-operated means for controlling the inflow of water, a water column communicating at its bottom with said means and at its 65 top with said trapped column, and a water supply inlet to said water column.

In witness whereof, I have hereunto signed my name in the presence of two subscribing witnesses.

QUIMBY N. EVANS
